UNITED STATES PATENT OFFICE

CESARE BARBIERI, OF NEW YORK, N. Y., ASSIGNOR, BY MESNE ASSIGNMENTS, TO THE VORTEX MANUFACTURING CO., OF CHICAGO, ILLINOIS, A CORPORATION OF DELAWARE

CAPPED CONTAINER

Application filed November 23, 1927. Serial No. 235,171.

This invention relates to "capped containers" adapted to serve as ice cream cups or the like, and constructed of a flexible material such as waterproof paper or the like.

5 It is an object of this invention to provide a paper container for ice cream and the like, said container preferably being of conical shape and provided with a cap or closure member having a crimped flange adapted to spring against the interior of the open end of the container, to have the upper margin of said container bend inwardly and crimped into locking engagement with the crimped flange of the closure to hold the same locked 10 in position against rotation.

It is also an object of this invention to provide a conical ice cream cup adapted to receive a crimped closure member or cap which is locked in position by bending a margin of 20 the cup inwardly and crimping said margin over the crimped portion of said closure member.

It is an important object of this invention to provide a conical container for ice cream, 25 liquids or the like, said container being provided with a cap having a crimped marginal flange which is adapted to be enclosed by bending and crimping a margin of the cup over said marginal flange to hold the cap 30 locked against rotation in the end of the cup.

Other and further important objects of this invention will be apparent from the disclosures in the specification and the accompanying drawings.

35 This invention (in a preferred form) is illustrated in the drawings and hereinafter more fully described.

On the drawings:

Figure 1 is a side elevation of an improved 40 capped conical container embodying the principles of this invention.

Figure 2 is a longitudinal central section of the container showing the same filled with a quantity of ice cream or the like.

45 Figure 3 is a top plan view of the capped container.

Figure 4 is a longitudinal central section of a filled container showing the crimped cap in position prior to the folding and crimping 50 of the margin of the container.

Figure 5 is a plan view of the crimped cap removed from the container.

Figure 6 is an enlarged fragmentary detail section of the upper portion of the closed container taken on line VI-VI of Figure 2.

As shown on the drawings:

The reference numeral 1 indicates a conical waterproof paper container or cup preferably constructed of treated paper cut in the form of a unitary blank, of substantially 60 quadrantal form having an arcuate edge and two substantial radial edges connected by means of an extension. The arcuate edge of the blank, after the same has been shaped, forms the marginal edge 2 of the conical container or cup. The container 1 is adapted to be filled with a quantity of ice cream 3 or any other desired substance, after which the container is adapted to be closed by means of an improved closure or cap consisting of a 70 paper or cardboard disc 4 having a crimped or plaited marginal flange 5 which projects upwardly and outwardly to afford an inclined or beveled edge. After a container has been filled with a quantity of ice cream or the 75 like the cap 4 is inserted into the open end of the conical container, as shown in Figure 4, with the crimped flange 5 springing tightly into frictional engagement with the inner face of the upper portion of the conical container. The cap is pushed downwardly so that the upper edge of the flange 5 is positioned a short distance beneath the upper edge 2 of the container as illustrated in Figure 4.

With the crimped cap seated in position within the open end of the container 1 the upper margin or rim of the container 1 is bent inwardly and downwardly and crimped over the crimped flange 5 of the cap 4. The 90 crimped margin 6 of the container is adapted to interfit with the crimped flange 5 of the cap as illustrated in Figure 6, thereby acting to hold the crimped cap 4 locked in position against rotation within the conical container 1.

The improved capped conical container hereinbefore described affords a sanitary package or cup for holding ice cream, liquids or other substances within the container be- 100

neath the crimped cap, the margin of which exerts an outward resilient pressure against the wall of the container, and furthermore affords a crimped margin with which the crimped inwardly turned or curled margin 5 of the container is adapted to lock to hold the cap in position against rotation, thereby producing a capped container admirably adapted for the dispensing of ice cream, ices 10 and other similar substances, as well as liquids.

I am aware that many changes may be made, and numerous details of construction may be varied through a wide range without 15 departing from the principles of this invention, and I therefore do not purpose limiting the patent granted hereon, otherwise than necessitated by the prior art.

- I claim as my invention:
- 20 1. A dispensing device comprising a container, a closure disc engaged in the open end of said container, a crimped marginal flange integrally formed on said closure disc adapted to resiliently spring against the inner wall of the container, said container adapted to have the margin thereof bend inwardly and crimped over the crimped flange of said closure disc to hold the same locked against rotation within the container.
  - 25 2. The combination with a container, of a closure disc seated in the open end thereof, and a crimped flange integrally formed on said disc and having resilient contact with the inner wall of the container, said container having the margin thereof bent inwardly and lockingly crimped over the crimped flange of said disc.
  - 30 3. In testimony whereof I have hereunto subscribed my name.
  - 35 40 CESARE BARBIERI.
